UNITED STATES PATENT OFFICE.

JAMES LUCENTE, OF NEW ROCHELLE, NEW YORK.

WINDOW-HOOK ATTACHMENT.

Application filed March 10, 1923. Serial No. 624,163.

This invention relates to a window hook attachment, and it more particularly relates to that type of hook which permits a storm sash to be removably hinged to a window frame.

An object of the invention is to provide a simple and inexpensive device made of wire for hingedly and removably holding screened frames or storm window on window frames.

Another object is to provide a strong hook made out of wire to be attached to a window frame and a coacting strong hook also made out of wire to be attached to an outside sash so as to permit the said sash to be removably hinged to the window frame.

Still another object is that of providing hinging and supporting members for storm or screen sashes and window frames which can be made of wire material to increase their strength and at the same time afford a shaping to closely adapt the same to the intended purpose.

Further objects will appear in the specification and drawings, it being understood that I do not limit myself to the exact construction illustrated, since manifestly it could be varied without changing the spirit of my invention.

Figure 1 is a front elevation of a window with a screen sash applied thereto and secured thereon by means of my improved hooks;

Figure 2 is a longitudinal section of a part 2—2 in Figure 1;

Figure 3 is a perspective view of my hooks unattached.

In the drawings a storm sash 1 which may be a screen or a window, is arranged in the front of a window frame 2. The sash 1 is of a removable type and for that purpose I provide hooks 3 and 4 which are secured respectively to the sash and window frame.

The hook 3 which is secured to the sash, is made of a single length of wire generally U shaped and is formed at the end of each leg with eyelets 4 and 5. The hook 3 is offset as at 6 so as to dispose the upper end 7 thereof forwardly of the eyelets so that when the hook is secured to the sash, (reference is had to Figure 2), which generally sets back into the window frame about one quarter of an inch from the outer face of the window frame, the portion 7 of the hook projects beyond the front of the window frame. It will here be noted that by means

of the offset 6, the weight of the sash is disposed in the rear of the hanging portion 7 of the hook and thereby the sash under its own weight is permitted to find its own seat in the window frame.

The hook 4 is also made of a single length of wire and generally U shaped and formed with eyelets 8 and 9. This hook is bent forwardly and upwardly adjacent its central and horizontal plane and its forward portion is curved slightly outward so as to form an easy sliding surface for the mating hook 3 when the same is hung thereon or taken therefrom. This hook as already pointed out is secured to the window frame 2. Screws 10 may be employed for securing hooks 3 and 4 to the sash and window frame respectively.

It will be seen that these hooks although simple in construction, they securely hinge the sash 1 to the window frame 2 without any danger of breakage or rust, because they can be made of any suitable rust proof and strong material. Another advantage of these hooks is that they can be shaped in any suitable manner to best serve their purpose. Once shaped these hooks will retain that shape for each has two legs to carry the weight and they are not apt to bend or get out of shape.

I would state in conclusion that while the illustrated example constitutes a practical embodiment of my invention, I do not limit myself strictly to the mechanical details herein illustrated, since manifestly the same can be considerably varied without departure from the spirit of the invention as defined in the appended claim.

Having described my invention I claim:

A screen fastener comprising a pair of complementary members, each of which consists of a single piece of wire bent intermediate of its ends to form a substantially U-shaped member, the legs of which terminate in eyelets, the hook member being bent upon itself along a transverse line to form an outwardly directed upturned lip having a convex upper surface, the eye member having its hook-engaging portion offset with respect to the plane of the body thereof, whereby when the members are engaged the offset portion of the eye is forced positively against the body of the hook with the plane of the hook body in advance of the plane of the eye body.

JAMES LUCENTE.
